CLAIM

The ornamental design for a cardiac patient gown, as shown and described.

DESCRIPTION

FIG. 1 is a front view of a cardiac patient gown showing my new design;

FIG. 2 is a rear view of the cardiac patient gown;

FIG. 3 is a left side view of the cardiac patient gown, a right side view being a mirror image thereof;

FIG. 4 is a top view of the cardiac patient gown; and,

FIG. 5 is a bottom view of the cardiac patient gown.
